UNITED STATES PATENT OFFICE

DUANE M. LILLIBRIDGE, OF ST. CHARLES, ILLINOIS

HAMMOCK FRAME

Application filed March 11, 1929. Serial No. 346,186.

The invention relates to hammock frames of a known type embodying a crown bar of inverted V-shape in transverse section and having slots near its ends and two sets of upwardly converging angle metal legs pivoted together and having fingers received in said slots. It is the object of the invention to provide a new and improved positioning of slots, fingers and leg pivots whereby the crown bar is not excessively weakened by said slots and the leg pivots are protected against rain and consequent rust.

With the foregoing in view, the invention resides in the novel subject matter herein-after described and claimed, description being accomplished by reference to the accompanying drawing.

Fig. 1 is a perspective view of a hammock frame constructed in accordance with the invention.

Fig. 2 is a side elevation showing the frame folded.

Fig. 3 is a fragmentary end elevation.

Fig. 4 is an enlarged vertical sectional view 25 on line 4—4 of Fig. 3.

Fig. 5 is a transverse sectional view on line 5—5 of Fig. 4.

Fig. 6 is a fragmentary disassembled perspective view.

50 A crown bar 7 is shown formed of angle metal with its side flanges disposed in downwardly diverging relation. Two sets of upwardly converging legs 8 and associated features of construction are employed for supporting the two ends of the bar 7 but in view of the fact that the structures at opposite ends of said bar are identical, only that at one end will be specifically explained.

Each of the legs 8 is provided with a flange 40 9 disposed in a plane transverse to the bar 7, and each of these legs embodies also a flange 10 in a plane extending longitudinally of said bar 7. The upper ends of the flanges 9 are overlapped and pivoted together at 11 and between their ends, said flanges are connected by a foldable spacer 12. Pivoted to the flanges 10, are two braces 13 whose upper ends are pivoted to a short vertical plate 14 which is secured to the bar 7 and provided with a 45 hammock hook 15. In securing plate 14 to

bar 7, said plate is preferably provided with oppositely bent tongues 16 passing through slots 17 in said bar. Unique connecting means is provided between the upper extremities of the flanges 10 and the end of the 55 bar 7.

The two downwardly diverging portions of bar 7 are each formed with a slot 18, these slots being comparatively small, being spaced inwardly from the end of bar 7, spaced upwardly from the lower edges of said bar and spaced downwardly from the ridge 19 of the latter. By forming the slots and positioning them in this manner, the bar 7 is not excessively weakened and an imperforate ridge 65 portion 20 is left between the slots. The leg pivot 11 is disposed in the angle of the bar 7 directly under the imperforate portion 20 and hence said pivot is protected to a large extent against rain and is consequently 70 shielded against rusting. The slots 18 receive upwardly converging fingers 21 formed integrally with the upper extremities of the flanges 10, the upper ends of said fingers being preferably curved somewhat toward 75 each other to prevent accidental upward knocking of the bar 7 from the legs when the frame is assembled for use.

In most instances, I prefer to provide the end portions of the bar 7 with upstanding 80 studs 22 instrumental in attaching a canopy (not shown).

When the frame is to be folded, for instance, to permit storage thereof in compact space or shipping or moving, the hammock is disconnected from the hooks 15, the legs 8 are swung inwardly toward each other upon release of the spacers 12, the fingers 21 are withdrawn from the slots 18 and the legs are swung inwardly as shown in Fig. 2, the pivots 85 of the braces 13 permitting these movements.

As excellent results are obtainable from the details disclosed, they are preferably followed. However, within the scope of the invention as claimed, minor variations may be 90 made.

I claim:—

In a hammock frame, a crown bar of inverted V-shape in transverse section, said bar being formed with two slots disposed one in 100

each of its downwardly diverging portions, said slots being spaced inwardly from one end of said bar, downwardly from the ridge of said bar and upwardly from the lower edges of the latter, two downwardly diverging legs 5 each having one flange in a plane transverse to said crown bar and another flange in a plane longitudinally of said crown bar, the two transverse flanges of said legs being pivoted together and terminated in the angle of 10 said crown bar immediately under the solid ridge portion of the latter between said slots, whereby said ridge portion protects the leg pivot against rain, the longitudinal flanges of 15 said legs being each provided with an upstanding integral finger, the two fingers being disposed in upwardly converging relation and passing through the aforesaid slots respectively.

20 In testimony whereof I have hereunto affixed my signature.

DUANE M. LILLIBRIDGE.
